UNITED STATES PATENT OFFICE

LE ROI E. HUTCHINGS, OF BUFFALO, NEW YORK, ASSIGNOR, BY MESNE ASSIGNMENTS,
TO REMINGTON RAND INC., OF NEW YORK, N. Y., A CORPORATION OF DELAWARE

CARD INDEX

Application filed March 4, 1924. Serial No. 696,800.

This invention relates to card indexes, and more particularly to the type of index in which a plurality of cards or card holders are maintained in overlapping, nested relation on a support with the edges of the cards or holders projecting one beyond another.

In indexes of this kind, cards or card-holders have been provided having a pair of oppositely directed, integral lugs or parts 10 stamped from the body of the card and adapted to engage cooperating, opposed flanges or parts on the support, whereby the cards or holders are prevented from lateral displacement thereon, while the two lugs provide 15 means for holding the cards in nested, overlapping relation and are adapted to be guided on the support by engagement with said flanges for permitting endwise sliding movements of the cards on the support. Indexes 20 of the kind stated, however, have certain disadvantages. For example, owing to the fact that the oppositely directed lugs or parts which cooperate with opposed flanges or parts on the support are stamped out of the 25 body of the card on lines which coincide with the outlines of the lugs, and these lugs are oppositely directed and at some distance apart, it is necessary, when inserting or attaching a card to the support, to bend or 30 deform both lugs and at the same time to engage them under the opposed flanges or parts of the support. This bending or de- 35 forming of the lugs relatively to the card body not only takes considerable time, but the consequent wear soon weakens or breaks off the lugs and renders the cards useless. Further, such operations require the user to 40 employ both hands, and owing to the fact that the lugs are merely cut out on a line coincident with their outlines and there is no space between the lugs and the adjacent body portions of the card, the lugs sometimes 45 engage the edges of the aperture and are prevented from accurately engaging the sup- porting parts.

One of the objects of this invention is to provide, in an index of this sort, a card, card-holder, or the like, having a single projecting member or tongue adapted to cooperate with a part on the support to prevent

transverse movements of the card in one direction, said projecting member or tongue also being adapted to maintain the cards in alignment and which nevertheless does not require bending or deformation in manipulating the card for insertion or removal thereof; and also to construct the card so that a part thereof, such as one of its edges, is adapted to be engaged by a part on the support to prevent the card from transverse movements in an opposite direction, to maintain the cards on said support. 55

Another object is to provide a card or card-holder for indexes of the sort mentioned, having an offset, laterally directed tongue, 60 which is partially surrounded by an aperture such that the edges of the tongues are prevented from engaging adjacent portions of the card body, thereby insuring the proper engagement of the card with the support. 65

Further objects of the invention are to provide a card index having cards or simplified form such that they may be quickly and positively inserted or attached to the index support by a single transverse movement, followed by a simple flexing of the card body, without requiring any bending or distortion of the projecting tongues relatively to the card body; also to provide a card which will positively nest with the next adjacent card on the support by a simple sliding movement of the card on the support. 70 75

Still another object of the invention is to improve card indexes and index cards and the like therefor in other respects hereinafter specified and claimed. 80 85

In the accompanying drawings:

Fig. 1 is a fragmentary plan view of a card index comprising a series of nested cards and a supporting member therefor, said cards and support being formed according to a preferred embodiment of the invention. 90

Fig. 2 is a similar view, partly in section, showing two nested cards separated from the remaining nested cards of the series. 95

Fig. 3 is a face view of two of the nested cards removed from the support.

Fig. 4 is a transverse sectional elevation of the support on line 4—4, Fig. 1.

Fig. 5 is a cross section of three nested 100

cards, on line 5—5, Fig. 3, on an enlarged scale.

Fig. 6 is a fragmentary plan view similar to Fig. 1, showing the method of attaching a card on the support.

Fig. 7 is a face view of three detached cards showing one card being moved to interlocked or nested relation with the others.

Fig. 8 is a transverse section of the index 10 showing the method of attaching a card on the support.

Fig. 9 is a view similar to Fig. 1, showing a follower for engaging an end card of the series.

15 Fig. 10 is a face view of a blank from which a card of slightly modified form is produced.

Fig. 11 is a rear view of the modified form of card produced from said blank.

Fig. 12 is a cross section thereof on line 20 12—12, Fig. 11, on an enlarged scale.

Fig. 13 is a view similar to Fig. 9, showing the flanges on the back member in section to illustrate the frictional engagement between the follower and the back member.

25 Fig. 14 is a detailed sectional view through the follower shown in Fig. 9, particularly illustrating the handle member thereon.

Briefly described, the card index of the present invention includes a plurality of 30 cards, card-holders or the like, each of which is provided with a single tongue or part which projects outwardly or is offset from the plane of the body portion, and which is adapted to permit the cards to be nested in 35 overlapping relation with a portion of each card projecting beyond the other. This tongue is provided with a laterally extending portion adapted to cooperate with a retaining flange or part on a supporting member to permit 40 sliding movements of the cards on the support and prevent lateral movements thereof in one direction. The support is further provided with a part adapted to engage a part of each card, such as the side edge 45 or some part of the card body other than the tongue, to prevent lateral movements of the cards in an opposite direction. The cards are so formed that they may be engaged with or attached to the support by a single trans- 50 verse movement of the card, followed by a slight bending movement thereof.

In the preferred form of the invention shown in the drawings, each card A comprises a body portion 10, and a projecting 55 tongue 11 which is offset rearwardly, preferably in a plane at a slight angle from the body portion. The tongue 11 is arranged within the area of the body portion, preferably about midway between its side edges and 60 is connected to the body portion adjacent the top edge 12, as shown. The tongue 11 is formed with a laterally extending part 13, preferably terminating in a semicircular outline, as shown, and the lower edge of this part 65 13 merges into an inclined lower edge 14 on

the tongue, which terminates in a rounded side edge 15 adjacent the juncture of the tongue 11 with the body 10 of the card. The other side of the part 13 is connected to a short, substantially straight side edge 16 of 70 the tongue which also connects with the body portion. The tongue 11 is preferably given a permanent angular set relatively to the body portion, so that its free edge is always out of the plane of the card body, thereby 75 permitting it to pass back of another card when moved into nesting relation thereto. This is done in any suitable way, as by scoring the card at the juncture of the tongue with the body portion, as at 17, and then 80 bending the tongue rearwardly along this line. The tongue is preferably die cut and integral with the card and may be either stamped directly out of the body portion 10, as shown in Figs. 1—9, or the card may be 85 formed of a die-cut blank A', see Figs. 10—12, such that an offset tongue 11^a is provided at one end, which is adapted to be folded over against the body portion 10^a along the line 12^a and secured to the body portion adjacent 90 the line 12^a, as by staple or the like 18.

The supporting member B of the index is preferably formed of sheet-metal and comprises a back 20 of slightly greater width than the cards A, and which is formed or provided 95 between its side edges with a card tongue retaining and guide member 21 which preferably extends from end to end of the support, and has a flange or part 22 spaced from the back member, beneath which the tongues 100 on the cards are adapted to be engaged.

To attach a card to the support, or to insert one or more cards into a series of cards on the support, the card is moved sideways, see Fig. 6, so as to direct the tongue 11 beneath the flange 22, the left-hand portion of the card body 10 meanwhile passing over this flange 22 towards the left. When the tongue 11 has been properly engaged, the movement will be arrested by the engagement of the side edge 16 with the free edge of the flange 22. The support 20 is further provided with means for engaging a portion of the card body 10, such as the right-hand side edge 25, so that after the tongue 11 has been engaged 115 beneath the flange 22, the card will be prevented from lateral movements on the support towards the right. The means shown for this purpose comprises a marginal side wall or part 26 having a flange 27 which is 120 spaced from the back wall 20 and extends inwardly over the same. After the tongue 11 has been positioned beneath the flange 22, the body portion 10 of the card is preferably bent or flexed, see Fig. 8, so that the right-hand edge 25 thereof may be directed under the overhanging flange 27. The distance between the side wall 26 and the free edge of the flange 22 is such that a limited side play of 125 the card is permitted, so that the card, or a 130

plurality of the nested cards, may be moved endwise freely on the support B, without binding between the support and the edges 16 and 25 of the card or cards, while nevertheless the tongue or tongues 11 cannot be unintentionally disengaged. The die-cut tongues 11, Figs. 1-9, instead of being formed by a single cut in the body 10 along the margin of the tongue, as has been the practice heretofore in forming such tongues, is formed by cutting away entirely a portion of the card body around the sides and bottom of the tongue, thus leaving an aperture 30 between these edges and the adjacent parts of the card body, see particularly Figs. 6 and 7. The upper portions of the card adjacent the aperture 30 are formed so as to provide edges 31 which preferably extend substantially parallel with the top edge 12 of the card. The tongues 11, being spaced from adjacent portions of the card bodies, are prevented from engaging and sticking thereto, so that they are always properly offset and alined to positively nest behind the body portions of adjacent cards. The provision of the inclined edges 14 permits the top edges 12 of the cards to be guided easily and without obstruction over the tongues 11. The edges 31 form stops to position the cards in parallel nested relation, with their lower edges exposed and spaced to the desired extent, and as parts of the card are cut away at these edges 31, the cards can move to nested relation but will not bind, so that the cards may be easily moved apart on the index when desired, as for the purpose of inserting other cards between the ends of a series, or for inserting or removing single cards when desired.

In the modified form of card shown in Figs. 10-12, the body portion 10^a has a portion thereof cut away to provide an aperture 35, adjacent the tongue 11^a, so that the edges of the tongue may be spaced from the body portion 10^a, as described in connection with the cards A. The tongue 11^a of the modified card is shaped and functions exactly like the tongue 11 of the card A.

A side wall 36 and flange 37 are preferably provided on the side of the support opposite to the side wall 26, beneath which the opposite edges of the cards are positioned.

While the cards, as regards their width and relative location of the tongues, are preferably proportioned substantially as shown in the drawings, the cards may, if desired, be of less width, as by dispensing with the left-hand portion of the card body to a point adjacent the aperture 30. In this case the left hand side wall 36 and flange 37 of the support B could be omitted, as it is only necessary to provide the flange 22 and side wall 26 to properly maintain the cards on the support.

It may sometimes be found desirable to provide the card index with a follower or device adapted to engage one end of the card

series to assist in maintaining them in nested relation. A suitable follower 40 for this purpose is shown in Fig. 9, which is preferably provided with a part or parts adapted to frictionally engage the top edge 12 of the upper or end card, as by means of the offset tabs or ears 41. The follower body may be formed of relatively stiff card or the like and is substantially rectangular, its side edges being adapted to have a fairly snug fit between the side walls 26 36 of the support B, so that it will be frictionally retained thereon in any position to which it is moved. As the ears 41 have frictional engagement with the edge of the adjacent card A by the wedging of the top edge of the card between the tabs or ears 41 and the body of the follower, the follower will always hold the series in close nested arrangement, but should it be desired to separate the series to insert or remove one or more cards, the follower may be moved on the support, as shown in Fig. 9, and the required number of cards will be moved with it in the same direction and held by the follower in spaced relation to the other cards. A handle or part 42 is preferably secured on the follower in any suitable manner, and is provided with a transparent pocket or the like 43 for the reception of a suitable designating or index slip. The opposite or lower end of the support B is preferably provided with a suitable stop portion 44 adapted to engage the opposite end of the card series to prevent the cards from endwise disengagement from the support.

I claim as my invention:

1. In a card index, a series of overlapping cards with their edges exposed one beyond another, each card having a body portion and a single tongue intermediate of the side edges thereof, said tongue being connected to, and offset rearwardly and downwardly from said body portion and being formed at its free end with a laterally extending part which is directed towards one side of said card body, a support for said cards, parts on said support adapted to be engaged by said laterally extending part of said tongue and said side of the card body by a transverse movement of said card towards said parts, said card, after such engagement, being prevented from transverse movements towards said side of said card, and a part on said support adapted to be engaged by the opposite side of said card to prevent transverse movements of said card toward said opposite side.

2. In a card index, a plurality of cards and a support for same, each of said cards having a body portion and a tongue extending downwardly at the rear of said body portion and having a part extending laterally towards one edge of said card and which is spaced from said body portion by an aperture formed in said body portion adjacent said tongue, a part on said support adapted to be

engaged by said tongue whereby said card is adapted to have lengthwise sliding movements on said support, and said tongue being adapted to pass behind an edge of an adjacent card to permit said cards to overlap in nested relation on said support.

3. In a card index having a series of overlapping cards with their edges exposed one beyond another, each card having a body portion and a single tongue intermediate of the side edges thereof, a support for said cards, a retaining part on said support with which said tongue is adapted to engage to prevent transverse movements of said card in one direction, a part on said support adapted to engage said card body to prevent transverse movements of said card in an opposite direction, a fixed part on said support adapted to engage one end of said card series to prevent endwise movement of said cards in one direction, and a detachable follower adapted to engage portions of said support and to have sliding movements relatively thereto, said follower having lugs adapted to engage an edge of a card of said series to maintain said cards in overlapping relation on said support.

4. In a card index, a plurality of cards and a support for same each of said cards having a body portion, a single tongue extending downwardly at the rear of said body portion and having a part extending laterally towards one edge of said card and which is spaced from said body portion by an aperture formed in said body portion adjacent said tongue, and is connected thereto along a line substantially parallel with the upper and lower edges of the card body, said aperture also defining stop portions on said card body which are substantially aligned with said line of connection and which define the adjacent portions of said aperture, said tongue being adapted to pass behind an edge of an adjacent card to permit nesting of said cards with said edge of said card engaging said stop portions, a part on said support adapted to be engaged by said tongue to permit lengthwise movement of said cards on said support and for preventing lateral movements of said card in one direction, and means for preventing lateral movements of said card in an opposite direction.

5. In an index or file, an index card comprising a strip of material having a tongue struck therefrom, said tongue extending inwardly from a marginal portion of said card, and having a tab portion extending toward a side edge of said card, substantially the entire length of said tab portion being separated from said marginal portion by an opening in said card.

6. In an index or file, an index card comprising a strip of material, having a portion struck therefrom adjacent a marginal portion thereof, a part of said struck-out portion being removed from and the remainder retained

in connection with said card adjacent said marginal portion, forming a tongue member, the opening formed by the part of said struck-out portion which is removed providing a space through which said tongue may be manipulated.

7. In an index or file, a plurality of index cards, a supporting member for slidably mounting said cards, a card stop on one end of said member, a follower slidably mounted on said member for holding said cards in position thereon, and a label holder mounted on said follower.

8. In an index or file, a plurality of index cards, a supporting member for slidably supporting said cards, a card stop at one end of said member, a follower slidably on said member for engaging and holding said cards, and an operating handle for said follower formed to removably mount a label.

9. In an index or file, a plurality of index cards, a supporting member having means slidably supporting said cards, a card stop at one end of said member, and a follower having slidable and frictional engagement with said means for retaining said cards in adjacent relation on said support.

10. In an index or file, a plurality of index cards formed for overlapping interfitting engagement, a supporting member having guide flanges at opposite edges for receiving portions of said cards and retaining them in slidable engagement on said member, a card stop at one end of said member, and a follower formed of stiff sheet material, rectangular in form, having the opposite edge portions slidably and frictionally engaged with said guide flanges, said follower being adapted to retain said cards in interfitting relation on said member.

11. In an index or file, a card-retaining strip provided with an inwardly directed flange, an index card slidably mounted thereon, having a section removed to provide a tongue attached to one marginal portion, said removed section permitting free manipulation of the tongue relative to the card, a tab on said tongue projecting toward one edge of said card to engage under said flange and said tongue having a side edge freely engaging the edge of said flange and positioning said card for sliding movement thereon, and means engaging the opposite edge of said card to retain said side edge adjacent said flange.

12. In an index or file, a card-retaining strip provided with an inwardly directed flange, a series of index cards mounted thereon in nested overlapping relation, each of said cards being formed with a tongue attached to one marginal portion, each card having a section removed contiguous to the edge of said tongue to permit free manipulation thereof, a tab extending laterally from said tongue to engage under said flange, said

- tongue having a side edge between the tab and marginal portion for engaging the edge of said flange, said removed section providing shoulders on said marginal portion to engage the edge of an adjacent card, and a back
- 5 member carrying said strip and having a flange engaging an edge of said cards to retain said side edges engaged with the edge of said flange on said strip, whereby said cards may have free sliding movement longitudinally on said strip.
- 10 13. In an index or file, an index card having a section removed to provide a tongue extending inwardly from a marginal portion and having the edge spaced from the adjacent portions of the card to permit free manipulation, a tab extending laterally from said tongue, and said tongue having a side edge between said tab and marginal portion adapted to form an abutment.
- 15 14. In an index or file, an index card having a section removed to provide a tongue extending inwardly from a marginal portion and having the edge spaced from the adjacent portions of the card to permit free manipulation, a tab extending laterally from said tongue, said removed section providing inner edges on said marginal portion to engage the edge of a nested card and limit interfitting of two cards, said tongue having its end formed with the edge extending in angular relation to said inner edges, whereby other cards may be freely nested between the tongue and card against said inner edges.
- 20 15. In an index or file, an index card having a section removed to provide a tongue extending inwardly from a marginal portion and having the edge spaced from the adjacent portions of the card to permit free manipulation, a tab extending laterally from said tongue, said removed section providing inner edges on said marginal portion to engage the edge of a nested card and limit interfitting of two cards, said tongue having its end formed with the edge extending in angular relation to said inner edges, and said tongue being formed in offset relation to said card, whereby other cards may be freely nested between the tongue and card against said inner edges.
- 25 16. In an index or file, an index card provided with a tongue directed inwardly from the lower marginal portion thereof, and an upwardly directed shoulder extending parallel with said marginal portion to one side of the connecting point between said tongue and said card.

LE ROI E. HUTCHINGS.

CERTIFICATE OF CORRECTION.

Patent No. 1,743,274.

Granted January 14, 1930, to

LE ROI E. HUTCHINGS.

It is hereby certified that error appears in the printed specification of the above numbered patent requiring correction as follows: Page 1, line 72, for the word "or" read "of"; page 3, lines 42 and 43, strike out the words "edges of the" and insert the same before the word "tongue" in line 42; page 4, line 75, claim 7, and line 102, claim 10, for the misspelled words "slidaby and sidably" read "slidably"; page 5, line 40, claim 15, for "lateraly" read "laterally"; and that the said Letters Patent should be read with these corrections therein that the same may conform to the record of the case in the Patent Office.

Signed and sealed this 4th day of March, A. D. 1930.
